COMBINED TABLE AND CHAIRS

Amedeo Maneus, Rosedale, N. Y.

Application June 23, 1947, Serial No. 756,451

6 Claims. (Cl. 155—123)

1

The present invention relates to tables and chairs and more particularly to tables provided with storage facilities adapted to receive the chairs.

It is an object of the invention to provide a table having recesses and a supporting means adapted to receive a chair which will maintain the chair in a position elevated from the floor.

A further object of the invention is to provide a table having supporting facilities adapted to hold a chair, the supporting facilities being of a type which will permit the chair to be readily removed or replaced.

Still another object of the invention is to provide a chair comprising a back member which may be readily folded to permit the chair to be placed into the storage recess of the table.

It is a feature of the invention that the seat of the chair will be visible when the chair is stored in the space provided for this purpose in the table. The chair may thus have a seat of suitable colored material in order that the seat may provide a pleasing and decorative appearance and give the effect of being an integral part of the table.

It is a further object of the invention to provide a chair comprising a handle member which will facilitate the removal or replacement thereof with respect to the table and which at the same time will present a pleasing appearance when the chair is stored in the table. The handle may also serve as a stop for the folding back.

For further comprehension of the invention, and of the objects and advantages thereof, reference will be had to the following description and accompanying drawing and to the appended claims in which the various novel features of the invention are more particularly set forth.

In the accompanying drawing forming a material part of this disclosure:

Fig. 1 shows a perspective view of a table embodying the invention, partly broken away.

Fig. 2 is a fragmentary sectional view taken in a vertical plane passing through the line 2—2 of Fig. 1.

Fig. 3 is a fragmentary sectional view, in elevation, taken along the line 3—3 of Fig. 2.

Fig. 4 is an enlarged fragmentary sectional view taken along the line 4—4 of Fig. 3.

Fig. 5 is a view in side elevation of a chair.

2

Fig. 6 is a perspective view of the chair shown in folded condition.

Fig. 7 is a fragmentary perspective view of another table embodying the invention.

Figs. 8 and 9 are perspective views of modified forms of chairs.

Referring to Fig. 1, the table 11 comprises the usual top 12 and legs 13. The legs and top are shown joined by the four side members 14, 15, 16, and 17. Disposed beneath the table top 12 is a horizontal supporting member 18 comprising a longitudinal bar 19 and four supports 20 which extend to the corners of the table.

In each of the side members 14 to 17, a cutout portion 21 is provided. These cutout portions are shown as being semi-circular in shape. The semi-circular shape is used when a chair is equipped with a round seat. If a chair having a square seat, as shown in Figs. 8 and 9, is to be used, then the cutout portion 21 will have the shape of a rectangle. Disposed on either side of cut-away portion 21 there is a horizontally extending hook member 22.

A chair in accordance with the invention is shown in Fig. 5. The chair comprises a plurality of legs 51 and a back member 52. Legs 51 support a seat 53 which is shown provided with a padded section 54. Seat 53 is provided with a backwardly extending handle 55. Handle 55 is shaped to extend close to and parallel to back member 52 when the back member is in the elevated position illustrated in Fig. 5. Back member 52 is secured to seat 53 by pivots 56 which are shown extending a substantial distance beyond the lateral portions thereof and which are illustrated as being provided with cylindrical heads shaped for engagement with hook members 22.

Seat 53 may be square in shape as shown in Figs. 8 and 9. If such a square seat is used, the back member 52 may be shaped as shown in Figs. 8 and 9 to conform closely to the shape of the seat. In either type of chair the padded seat portion 54 may have any desired form of construction and the covering material therefor may bear a decorative design or may be colored to fit into a decorative plan for a room.

In operation, a chair as shown in Fig. 5 may be stored in the table by pivoting back member 52 about pivots 56 to the position 52'. With the

chair thus folded, it may be conveniently grasped by means of handle 55. The front legs are then extended upwardly beneath the table and over longitudinal bar 19. The seat is then raised upwardly and after pivots 56 have been raised a sufficient distance, the chair is drawn slightly outwardly and then lowered so that hook members 22 will support the protruding heads of pivots 56. The chair will thus be stored beneath the table so that only its seat will be visible as shown in Fig. 1 and the seat will present a pleasing and decorative appearance. Moreover, the chair will appear to form an integral part of the table.

In order to remove the chair, the handle 55 may be grasped to disengage pivots 56 from hook members 22, thus permitting the seat of the chair to be lowered and the legs to be withdrawn from engagement with longitudinal bar 19. Back member 52 of the chair is then swung to its elevated position, as illustrated in Fig. 5, and the chair is ready for use. In side board 16, the cutaway portion is slightly displaced from that of side board 14 in order that the chairs positioned in opposite side boards will have their legs in interleaving relationship. When a chair is placed in either side board 15 or 17, its legs instead of engaging longitudinal bar 19 will engage two of the adjacent supports 20.

In Fig. 7 a large table 11' is shown to accommodate a plurality of chairs. In other respects this form of the invention is similar to the previous form.

It will thus be seen that the invention provides a table which is of extremely simple construction, and which comprises no moving parts. In the chair, the back member is secured by a simple pair of pivots having heads adapted to engage the hooks provided for this purpose in the table. It will be seen that the invention is extremely rugged and capable of manufacture at comparatively low cost.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a device of the class described, a table having a top and supporting means for the top, a chair comprising a seat member, a plurality of legs fixedly secured to the seat member, projecting members extending from the seat member, a side board in the table positioned adjacent to and beneath the table top having a cutaway portion therein shaped to conform to the seat portion of the chair, and supporting means secured to the table and adapted to support the chair by removable engagement with the legs and the projecting members in a position in which the seat member is substantially vertical and in conformity with the cutaway portion of the side board.

2. In a device of the class described, a table having a top and supporting means for the top, a chair comprising a seat member, a plurality of legs fixedly secured to the seat member, projecting members extending from the seat member, a side board in the table positioned adjacent to and beneath the table top and having a cutaway portion therein shaped to conform to the seat portion of the chair, transverse supporting means

secured to the table and adapted to support the chair by readily removable engagement with the legs thereof, and hook means disposed adjacent the cutaway portion and shaped for removable engagement with the projecting members and further disposed to maintain the seat member in a substantially vertical position in conformity with the cutaway portion of the side boards with the chair legs in engagement with the transverse supporting means.

3. In a device of the class described, a table having a top and supporting means for the top, a side member adjacent to the top and having a portion thereof cutaway, a pair of hook members disposed on opposite sides of the cutaway portion and adjacent to the periphery thereof, a supporting member disposed beneath the top, a chair comprising a plurality of legs and a seat shaped to conform to the cutaway portion and secured to the legs, a back member shaped to conform to the seat, and headed pivot means securing the back member to the seat and disposed for removable engagement with the hook members with the chair positioned beneath the table and with the back member pivoted to a position adjacent the chair legs and with at least one of the chair legs extending over the supporting member and with the seat positioned in conformity with the cutaway portion of the side member.

4. In combination with a table having a top supported on legs and a depending side member, a support bar beneath the top spaced from and extended parallel to the side member, a chair having a seat member supported on front and rear legs, the side member being formed with a cutout conformed to the shape of the front portion of the seat of said chair, trunnions extended from diametrically opposite sides of the seat of said chair midway between the front and rear legs, and hook members mounted on the side member on opposite sides of said cutout to receive said trunnions, whereby said chair may be disposed beneath the top with the front legs resting on said support bar, with said trunnions engaged in said hook members and with said seat in said cutout.

5. In combination with a table having a top supported on legs and a depending side member, a support bar beneath the top spaced from and extended parallel to the side member, a chair having a seat member supported on front and rear legs, the side member being formed with a cutout conformed to the shape of the front portion of the seat of said chair, trunnions extended from diametrically opposite sides of the seat of said chair midway between the front and rear legs, and hook members mounted on the side member on opposite sides of said cutout to receive said trunnions, whereby said chair may be disposed beneath the top with the front legs resting on said support bar, with said trunnions engaged in said hook members and with said seat in said cutout, and a handle extended from the seat of said chair.

6. In combination with a table having a top supported on legs and a depending side member, a support bar beneath the top spaced from and extended parallel to the side member, a chair having a seat member supported on front and rear legs, the side member being formed with a cutout conformed to the shape of the front portion of the seat of said chair, trunnions extended from diametrically opposite sides of the seat of said chair midway between the front and rear legs,

and hook members mounted on the side member on opposite sides of said cutout to receive said trunnions, whereby said chair may be disposed beneath the top with the front legs resting on said support bar, with said trunnions engaged in said hook members and with said seat in said cutout, and a handle extended rearward from the seat of said chair, and a chair back pivotally supported on said trunnions to have an operative position rested on said handle when said chair is in use or an inoperative position extended along said front legs when said chair is disposed beneath the top.
